UNITED STATES PATENT OFFICE.

JOHN A. LAMONT, OF CHICAGO, ILLINOIS, AND LAWRENCE RICHARDSON, OF LOUISVILLE, KENTUCKY, ASSIGNORS TO AMERICAN STEEL FOUNDRIES, OF CHICAGO, ILLINOIS, A CORPORATION OF NEW JERSEY.

EQUALIZING ARRANGEMENT FOR SIX-WHEEL TRUCKS.

Application filed May 24, 1922. Serial No. 563,333.

To all whom it may concern:

Be it known that we, JOHN A. LAMONT and LAWRENCE RICHARDSON, citizens of the United States, residing, respectively, at Chicago, in the county of Cook and State of Illinois, and at Louisville, in the county of Jefferson and State of Kentucky, have jointly invented certain new and useful Improvements in an Equalizing Arrangement for Six-Wheel Trucks, of which the following is a specification.

This invention relates to an equalizing arrangement for six-wheel trucks.

One object of the invention is to provide a simple and efficient six-wheel equalizing truck arrangement whereby an equal division of the bolster end loads to the middle journal boxes on both sides of the truck is insured and, accordingly, any tendency of 20 said middle journal boxes to tilt is overcome.

Another object is to provide a simple, cooperative arrangement between the equalizing levers and the middle journal boxes 25 whereby there is no tendency to cramp said middle journal boxes against proper movements.

Another object is to provide a simple, durable and efficient six-wheel equalizing 30 truck arrangement adapted to meet the various requirements for successful commercial operation.

These and other objects are accomplished by means of the arrangement disclosed on 35 the accompanying sheets of drawings, in which—

Figure 1 is a fragmentary side elevation of a six-wheel car truck embodying our invention;

Figure 2 is a fragmentary top plan view of the same;

Figure 3 is an enlarged fragmentary longitudinal sectional view through one of the side frames of the truck and showing various 45 cooperating parts;

Figure 4 is a detail sectional view taken in the plane of line 4—4 of Figure 3; and

Figure 5 is a detail sectional view taken in the plane of line 5—5 of Figure 3.

50 The various novel features of our invention will be apparent from the following description and drawings and will be par-

ticularly pointed out in the appended claims.

Referring to the figures of the drawings, 55 it will be noted that the invention is illustrated in connection with a six-wheel car truck including side frames 10, only one of which is shown. The side frame structure and the associated parts on each side of the 60 truck being the same, reference in the detail description will be had to but one side of the truck.

Each side frame has openings 11 for end journal boxes 12, a relatively large opening 65 13 for the reception of an intermediate journal box 14 and other associated parts, and openings 15 for the reception of ends of transverse bolster members 16 which receive loads from the main bolster member 17. 70 It will be understood that the load taken by the main bolster member 17 is to be transmitted through the transverse bolster members 16, equalizing levers 18 and to the end journal box 12 through the side frame 10 75 and directly from the equalizing levers to the intermediate journal box 14. The outer ends of the equalizing levers 18 are interposed between and pivotally connected to the side walls 19 of the side frame 10 by 80 pins 20. These equalizing levers bow downwardly from their pivotal points 20 to form seat portions 21 for the ends of the bolster members 16 which rest upon such seat portions. The equalizing levers then extend 85 upwardly and inwardly longitudinally of the truck and terminate in horizontally extending portions which are telescopically arranged. More specifically, the inner end of the right hand equalizing lever is provided with a tongue 22 which is received within an end pocket 23 in the inner end of the left hand equalizing lever.

Preferably, the sides of the tongue 22 are provided with trunnions 24 which extend 90 into openings 25 formed in opposite sides of a sleeve 26 which fits over the tongue 22 and within the pocket 23. Also preferably the tongue 22, sleeve 26 and pocket 23 are made square in section to insure a 100 large bearing contact for reducing the tendency to wear the frictional engaging surfaces. However, the upper and lower surfaces of tongue 22 are convex to permit

2
a free vertical movement of the inner ends of the levers 18 as well as a relative longitudinal sliding movement. The sleeve, of course, upon becoming worn, may be replaced by a new sleeve.

Each equalizing lever 18 is provided with a bracket 27 for the reception of a removable friction plate 28 which rests upon a spring cap 29 which in turn sets over a plurality of concentrically arranged springs 30 located in spring pockets 31 at opposite sides of the journal receiving portion 32 of the intermediate journal box 14. The intermediate journal box 14 is guided in its vertical movements by guide members 33. Each of these guide members 33 is provided with projections 34 which are received within associated pockets 35 in each equalizing lever 18, and each guide member 33 is releasably held in its associated equalizing lever by passing a U-shaped pin 36 through a portion of the lever 18 and through the projections 34. Preferably the journal box guide members 33 are permitted a given amount of play in the equalizing levers to permit of slight angularity or movement to adjust themselves to the adjacent wearing faces of the intermediate journal box. It will be noted that the center of these journal box guides 33 are on a horizontal line passing through the lever fulcrum pins 20 so that any normal movement above or below such horizontal line given to the guide blocks 33, by virtue of being carried by the equalizing levers 18, is practically vertical and, accordingly, there is no tendency to cramp the journal box. The line drawn between the lever fulcrum pins 20 also intersects the middle journal box approximately on the horizontal line of force of the journal bearing. The bearing face of the lever spring seat or friction plate 28 also extends on this line so that the longitudinal movement of the lever spring seat or friction plate 28 relative to the spring cap 29 due to vertical movement of the levers is practically negligible.

Referring particularly to Figure 4, it will be noted that the intermediate journal box guides 33 have a sliding fit with the inner surfaces of the side walls 19 of the side frame 10 for holding the center line of equalizing levers on the center line of the side frame.

When the truck is curving, lateral movement of the middle pair of wheels and journal box relative to the end journal boxes and side frame is provided for by allowing necessary clearance between the inner surfaces of the side walls of the side frame and side walls of the spring pocket portion of the journal, and also by providing at the same time necessary bearing surface between the friction plates 28 and spring caps 29.

As mentioned above, the inner ends of

the equalizing levers are telescopically connected, such connection being over the middle journal box. Accordingly, there is insured substantially an equal division of bolster end loads on either side of the truck 70 to the middle journal box springs, thereby overcoming any tendency for the middle journal boxes to tilt or stand at an angle to the vertical.

It is our intention to cover all modifications of the invention falling within the spirit and scope of the following claims.

We claim:

1. In a six-wheel truck, the combination of a side frame, journal boxes associated therewith, and equalizing levers for distributing the load to said journal boxes, the inner ends of said equalizing levers being telescopically arranged to equalize the distribution of the load and to overcome any 85 tendency of the middle journal box to tilt.

2. In a six-wheel truck, the combination of a side frame, journal boxes associated therewith, equalizing levers for distributing the load to said journal boxes, the inner 90 ends of said equalizing levers being telescopically arranged to equalize the distribution of the load and to overcome any tendency of the middle journal box to tilt, and guide means carried by said equalizing 95 levers for guiding the intermediate journal box in its vertical movements.

3. In a six-wheel truck, the combination of a side frame, journal boxes associated therewith, and equalizing levers for distributing the load to said journal boxes, the inner ends of said equalizing levers being telescopically arranged to equalize the distribution of the load and to overcome any 105 tendency of the middle journal box to tilt, said telescopic arrangement permitting relative movement of said equalizing levers in a plurality of directions.

4. In a six-wheel truck, the combination of a side frame, journal boxes associated therewith, equalizing levers for distributing the load to said journal boxes, and guide members carried by said equalizing levers for guiding the intermediate journal box in 110 its vertical movements.

5. In a six-wheel truck, the combination of a side frame, journal boxes associated therewith, equalizing levers for distributing the load to said journal boxes, and guide members removably secured to said equalizing 120 levers for guiding the intermediate journal box in its vertical movements.

6. In a six-wheel truck, the combination of a side frame, journal boxes associated therewith, equalizing levers pivotally connected to 125 said side frame for distributing the load to said journal boxes, guide members carried by said equalizing levers for guiding the intermediate journal box in its vertical movements, the middle of the guiding surfaces of 130

said guide members lying in substantially the same horizontal plane of the pivotal points of said equalizing levers to prevent the intermediate journal box from being 5 cramped as a result of relative movement between such intermediate journal box and said equalizing levers.

7. In a six-wheel truck, the combination of a side frame, journal boxes carried thereby, equalizing levers pivotally connected to said side frame, springs carried by an intermediate journal box, and spring caps mounted on said springs, said equalizing levers operatively engaging said spring caps in substantially the same horizontal plane in which said equalizing levers are pivotally mounted for causing a minimum amount of relative longitudinal movement between said spring caps and equalizing levers as a result 20 of relative vertical movement between said equalizing levers and intermediate journal box.

8. In a six-wheel truck, the combination of a side frame, an equalizing lever operatively connected to said side frame, a guide member for an intermediate journal box carried by said equalizing lever and associated with said side frame in a manner whereby the longitudinal center line of said side frame 30 and equalizing lever substantially coincide.

9. In a six-wheel truck, the combination of a side frame having side walls, an equalizing lever mounted between said side walls and operatively connected to said side frame, 35 and a journal box guide member carried by

said equalizing lever and cooperating with the side walls of said side frame in a manner to maintain said side frame and equalizing lever in proper alignment.

10. In a railway car truck, the combination of a side frame having side walls, an equalizing lever mounted between said side walls and operatively connected to said side frame, and a member carried by said equalizing lever and cooperating with said side walls for maintaining said side frame and equalizing lever in longitudinal alignment. 40 45

11. In a six-wheel truck, the combination of a side frame, journal boxes associated therewith, equalizing levers movably mounted with respect to said side frame and arranged for distributing the load to said journal boxes, and guide members carried by said equalizing levers for guiding the intermediate journal box in its vertical movements. 50 55

12. In a six-wheel truck, the combination of a side frame, an intermediate journal box associated therewith, resilient means carried by said journal box, and equalizing levers for transmitting the load to said journal box 60 through said resilient means, the inner ends of said equalizing levers being telescopically arranged to neutralize any difference in load transmitted through said levers to said journal box. 65

Signed at Chicago, Illinois, this 15th day of May, 1922.

JOHN A. LAMONT.
